UNITED STATES PATENT OFFICE.

JOSIAH AUSTIN AND ROSSCO CHAMBERLAIN, OF EAST LIBERTY, OHIO.

GATE.

SPECIFICATION forming part of Letters Patent No. 331,673, dated December 1, 1885.

Application filed December 23, 1884. Serial No. 151,029. (No model.)

To all whom it may concern:

Be it known that we, JOSIAH AUSTIN and Rossco CHAMBERLAIN, of East Liberty, in the county of Logan and State of Ohio, have 5 invented a new and useful Improvement in Gates, of which the following is a full, clear, and exact description, reference being had to the annexed drawings, forming part of this specification.

10 This invention relates to automatic double gates; and it consists of certain improvements on the gates shown in Letters Patent No. 251,498, granted to us under date of December 27, 1881, No. 272,619, granted to us under 15 date of February 20, 1883, and No. 299,451, granted to us under date of May 27, 1884.

In the drawings, Figure 1 is an elevation of our improved double gate, partly in section; and Figs. 2, 3, and 4 are detail views.

20 A indicates the two gates, and B are the posts by which they are supported. Underneath the roadway is arranged a rock-shaft, C, which is journaled in bearings D, attached to the posts. The bearing D is made L-shaped 25 and is so arranged that one of its arms shall extend out from its post to form a bearing for the lower part of the hinge-rod E. On the lower end of said rod E, below its bearing, is secured a bevel segmental pinion, F, which 30 meshes with a bevel segmental gear, G, which is secured to the rock-shaft C.

Instead of forming the segmental pinion and gear with regular teeth, as shown in our Patent No. 272,619, we form the central part of 35 the gear with a plane surface, H, and the central part of the pinion with a toothless portion, I, which shall bear against said plane surface H when the gate is closed. The said plane surface thus serves to lock the pinion 40 until the segmental gear is moved by the push-rod J sufficiently to bring the tooth K into engagement with the teeth L M of the pinion, when the further movement of the gear will cause the pinion to turn and move the hinge-rod E, causing the gate to swing open.

45 A roller, N, is supported underneath the projecting arm of the L-shaped bearing D in position for bearing against the outer or back surface of the gear G, for supporting the latter at the upper end. The arm of the bearing

D, which supports the hinge-rod E, is intended to be made broad, so as to cover the pinion F and gear G, and form a housing for the same.

In order to provide for unlatching the gate in the act of opening it, the upper end of the hinge-rod E is formed with a crank, O, to which the upper end of the gate is attached, so that as the hinge-rod begins to turn the crank will slightly lift the free end of the gate and lift the latch P out of the keeper Q. The keeper Q is formed with four levers, R, independently pivoted in a support, S, and arranged in pairs. Each pair is provided with a retaining spiral spring, T, which forces their ends t outward and their ends s inward 65 against an intermediate stop, r. The two pairs of levers are arranged with their ends t toward each other, so that the gates when opened either way and then closed will be promptly stopped in closed position.

70 U indicates an inclined serrated catch supported on a post, V, in position for catching the gate by one of its bars X, when opened. The bar X is provided with a corresponding serrated plate, Y, secured to its lower edge 75 and inclined upward at its ends from its center, so as to be operative when the gate is opened either way, there being two catches, U, for each gate. The inclination of the catch U is such that the free end of the gate will be 80 lifted as it moves on the catch, and thus its momentum will be gradually checked. The act of closing the gate will lift it out of contact with the catch U.

85 While the hinge and the keeper Q are especially adapted to the automatic operation of the gate, yet as it is frequently necessary to open the gate by hand by raising the latch P without lifting the gate, it is found essential that the crank-rod E should remain stationary 90 at such times. It is further necessary to the successful operation of a crank-hinge gate that while the gate may be operated by a slide-bar, G, yet the gate should not be able to start from its normal or closed position and operate the 95 said slide-bar. This is the especial reason for giving the segmental form M I M to the pinion F and intermediate blank, H, in the rack on the slide-bar G. The blank H resists motion of both teeth M and holds the pinion still 100

while the gate is opened by hand, as stated, and it holds the pinion still in case anything leaning against the top of the gate gave the crank O a tendency to move. The keeper Q 5 stands across the center of the plane of the gates, and either of the detents R on one side of it may be sprung in to admit the gate between them as the gate is closed one way or the other; but these detents are not provided 10 with any other means to move them, so that the gate cannot be opened automatically without some means of lifting the latch P. This means I provide in the cranked hinge, which lifts the gate bodily. It is especially necessary 15 that a gate opened mechanically by being permitted to swing down at incline, as this does, should be provided with means for gradually overcoming the momentum acquired. To this end I have provided the inclined serrated 20 catches Y U. The gate must be lifted to disengage these catches, and this again is accomplished by the lifting-crank O.

What we claim is—

1. The combination, with a gate and post, 25 of the hinge-rod E, journaled vertically in brackets secured to the post and provided with the crank O at its upper end, the said gate being hinged at its upper edge upon the said crank and at its lower edge upon the rod 30 of the crank, a pinion, F, secured on the

lower end of the crank and provided with teeth M L at each side of the plane of the gate and a blank segment, I, between the teeth M, and a slide-rod or rack, G, having a blank section, H, adapted to bear against both teeth M at once, and having a tooth, K, at each side of the space H, adapted to engage the teeth M L, substantially as shown and described, for the purpose specified. 35

2. The combination of the post B, the hinge-rod E, provided with a crank, O, and vertically journaled on the post, the gate A, hinged upon said rod and crank, the latch P on the gate, the keeper Q, secured on the ground beneath the edge of the gate and provided with the stops r, and the stops R, pivoted to the keeper Q in the path of the latch P, and provided with projections s and the springs T, substantially as shown and described. 40

3. The combination of the gate A, the 45 cranked hinge-rod E therefor, the serrated plate Y, secured to the gate and inclined upward each way from the center, and the serrated catch U and post V, substantially as shown and described. 50

JOSIAH AUSTIN.

ROSSCO CHAMBERLAIN.
